UNITED STATES PATENT OFFICE.

DAVID E. HUNTER, OF MUSKEGON, MICHIGAN, ASSIGNOR TO THE SHAW-WALKER CO., OF MUSKEGON, MICHIGAN, A CORPORATION OF MICHIGAN.

INDEX TAB FOR GUIDE CARDS.

Application filed January 19, 1923. Serial No. 613,605.

To all whom it may concern:

Be it known that I, DAVID E. HUNTER, a citizen of the United States, and a resident of Muskegon, in the county of Muskegon and State of Michigan, have invented certain new and useful Improvements in Index Tabs for Guide Cards, of which the following is a specification.

This invention relates to improvements 10 in index tabs for guide cards, employed in vertical filing systems, and the object of the invention is to provide a tab made of sheet metal and formed in such a way as to have ample stiffness without reinforcement, 15 and having its margins treated in such a manner as to eliminate sharp corners and edges, and thus avoid the possibility of the operators cutting their fingers in manipulating the cards.

20 The tab embodying the invention is clearly illustrated in the accompanying drawings, in which—

Fig. 1 is a view in front elevation of a 25 guide card with tab applied thereto, and index slip partially inserted.

Fig. 2 is a rear view of the tab removed, shown in perspective, and

Fig. 3 is a view in vertical section, taken 30 on line 3, 3 of Fig. 2.

In Fig. 1 a guide card A is shown, such 35 as is commonly used in vertical filing systems, and consists of a sheet of relatively stiff cardboard, having a metal tab B riveted to its upper edge, and an eyelet tab a at its lower edge. A portion of the tab B projects above the margin of the card and forms a slot into which is inserted an index slip C, which is visible through an opening in the front wall of the tab.

40 Referring now to the construction of the tab, the same is preferably stamped from a sheet of thin metal in the form of a blank and then bent into its final form, consisting of front and rear walls 1 and 2 of substantially the same size and shape, connected together at the top edge 3, which is the line 45 of folding of the blank. Each wall portion is shaped somewhat after an arrow-head, with its pointed end extending downwardly and away from the folded edge 3. The lower portions of the walls 1 and 2 are triangular in shape and form the two complementary card engaging sections 1^a and 2^a which straddle the upper marginal edge 50 of the card symmetrically, and are fixed

thereto by eyelets which are riveted through registering holes 4 punched in the walls at the three corners of the triangle, the upper eyelets being inserted just below the top edge of the card A.

The projecting portion of the tab consists of the doubled over or folded front and rear walls lying between the top or folded edge 3 and the line of the upper eyelets, the general shape being that of a truncated triangle, that is, with the end edges converging or inclined inwardly at an angle of, say, sixty degrees to the vertical. Along the inclined side edge 5, 5, of the front wall 1, the metal is extended beyond the corresponding edges of the rear wall and the marginal portions doubled back against the rear face thereof, forming beads 6, 6 throughout the length thereof. The corners of the tab are rounded and formed by carrying the beads 6, 6 inwardly from the ends, the material being cut back throughout the corner portions. It is to be observed that the top edge 3 is crimped or folded double along its margin, thus forming a rounded bead along 75 said edge which merges with the rounded corner beads 6, 6. Immediately below the beaded top edge 3 the material is bent outwardly and then downwardly along the line 7. Thus the rear wall is spaced from the 80 front wall in parallel relation thereto and forms the pocket or slot in which the insert slip C is retained. The corresponding inclined side edges 8, 8 of the back wall 2 are spaced or cut back a short distance inwardly 85 from the beaded edges 5, 5 of the front wall, and since they are not exposed to contact 90 with the fingers, the beaded edge is omitted.

In the front wall 1 of the projecting portion of the tab is an elongated rectangular 95 sight opening 9 for the index designations appearing on the index slip C, which is insertable endwise from either side of the tab in the manner shown in Fig. 1. The upper edge of the card A provides the lower edge 100 of the slip receiving slot.

In the rear wall 2 immediately behind the sight opening 9 is a smaller opening 10, whereby access may be had to the back of the slip C for facilitating the removal or 105 insertion thereof. Just below the smaller opening 10 is a narrow slot 11 to be resorted to in the process of mounting the tabs upon the cards as a guide to positioning the same therein symmetrically with 110

the edge so as to insure an insert slot of uniform height. Thus the slot 11 being parallel with the top edge 3, the tab will be properly mounted if the edge of the card 5 coincides with the lower edge of the guide slot, Fig. 2.

Separating the opening 10 and guide slot 11 in the back wall of the tab is a narrow strip or tongue 12 which is offset or sprung inwardly, thus acting as a tension grip to engage the insert slip and to hold it in place.

The advantage of a tab of this character resides in the protection to the file operators from sharp corners and edges, which 15 frequently result in cut fingers, especially when filing is being done speedily and the guide cards fingered in rapid succession.

A further advantage lies in the degree of stiffness afforded by the double wall construction which eliminates the necessity of a tab formed at the edge of the card itself, and serving as the foundation of the metal tab. In this way guide cards of a uniform 20 size and contour may be used throughout a single file, it being only necessary to position the metal tab at different points along the top edge in order to secure the various insets for dividing and subdividing the file.

Manifestly a suitable material other than 25 metal may be employed and the tab otherwise modified without departing from the spirit of the invention.

I claim—

1. A tab adapted for attachment to a 30 guide card comprising double wall portions forming a pocket therebetween and provided with a beaded top edge and inclined end edges meeting said top edge in rounded corners, one of the edges at each end being 35 spaced back from the other and having its marginal portion bent double to form a bead extending throughout said rounded corners.

2. A tab comprising double wall portions

adapted to project beyond the edge of a 45 guide card and to form therebetween a longitudinal open-ended pocket to receive an index slip, the front wall of said projecting portion having a sight opening therein and the rear wall a smaller opening 50 together with a narrow guide slot adapted to register with the edge of the guide card, and separated from said smaller opening by a narrow strip of metal bent inwardly to provide a tension grip for said index 55 slip.

3. The combination with a guide card, of a metal tab comprising double wall portions folded along the top edge, the lower portions of said walls straddling the edge 60 of the card and fastened thereto with the upper portions projecting beyond the edge of said card to form an index slip retaining slot therebetween, the ends of said projecting portions having convergent edges 65 meeting the folded edge in rounded corners, one edge being spaced outwardly from the other and having its marginal portion bent double to form a bead.

4. The combination with a guide card, 70 of a metal tab comprising complementary front and rear walls folded double along the top edge and adapted to straddle the edge of said card throughout the lower portions thereof with the upper portions projecting beyond the card edge, said upper portion having the exposed side edges inclined inwardly toward and meeting the top edge in rounded corners, the said side edges of the front wall being bent double to form 75 a bead throughout the exposed portions thereof, and the corresponding edges of the rear wall portion cut back from said beaded edges.

In witness whereof I hereunto subscribe 80 my name this 15th day of December, A. D., 1922.

DAVID E. HUNTER.
